UNITED STATES PATENT OFFICE

GEORGE S. CLEMENTS AND DANIEL S. LIGHT, OF MILL CREEK,

RAILROAD-RAIL FASTENING.

SPECIFICATION forming part of Letters Patent No. 239,781, dated April 5,

Application filed January 6, 1881. (No model.)

To all whom it may concern:

Be it known that we, GEORGE S. CLEMENTS and DANIEL S. LIGHT, of Mill Creek, in the county of Huntingdon and State of Pennsylvania, have invented a new and Improved Joint-Bar for Railroad-Rails; and we hereby declare the following to be a full, clear, and exact account thereof, reference being had to the accompanying drawings, making part of this specification, in which—

Figure 1 is a perspective view, showing the ends of two rails joined with our device. Fig. 2 is a vertical cross-sectional view of the rail and tie or joint bar. Figs. 3, 4, and 5 are details to be referred to.

The object of our invention is to provide a means for securely fastening the ends of track-rails of railroads; and our invention consists in a joint-covering device composed of two pieces of rolled metal clasping the ends of contiguous rails, and secured by a key which gives a lateral pressure, and is, in turn, secured by spikes driven in offsets provided for the purpose, as hereinafter more fully described and claimed.

In the said drawings, A A' represent two track-rails, the ends of which abut against each other in the usual manner. A plate of steel or iron, B, is bent to conform to the shape of the rail, starting from beneath the T on one side, passing down and over the foot of the rail, and beneath the rail to the opposite edge of the foot, when it is turned or lapped

over, as seen at a a. Another plate of iron, I, passes from beneath the edge T of the rail, down over the foot and its edge passes beneath the lap b b pass through the rails and through plate B, when the lap is made, and is left for a longitudinal key, E, which is driven in, crowds the edges of the plate together by its lateral pressure and holds it firmly. In the bight of the lap in I are cut recesses e e, to receive spikes to hold the plate. In the side of the key E are recesses i i, which, when the key is driven in, register with recesses e e, and spikes secure both the plate and the rail. Where plate B passes around the foot of the rail recesses o o are cut in the plate to add to the security of the joint.

Having thus described our invention, we claim as new, and desire to secure the same by Letters Patent, is—

The improved rail-joint fastening, consisting of a plate B, clasping the rails on the bottom, and provided with lap a, as shown in Fig. 1, in combination with the said lap and key being provided with spikes for the purpose set forth.

GEO. S. CLEMENTS
DANIEL S. LIGHT
